UNITED STATES PATENT OFFICE.

THOMAS C. DUFFIELD, OF BRIDGETON, NEW JERSEY, ASSIGNOR TO PARKER BROTHERS
GLASS MANUFACTURING COMPANY, OF BRIDGETON, NEW JERSEY.

BOTTLE-BLOWING MACHINE.

1,087,283.

Specification of Letters Patent.

Patented Feb. 17, 1914.

Original application filed April 3, 1912, Serial No. 688,213. Divided and this application filed September 13, 1912. Serial No. 720,114.

To all whom it may concern:

Be it known that I, THOMAS C. DUFFIELD, a citizen of the United States, residing at Bridgeton, in the county of Cumberland and State of New Jersey, have invented certain new and useful Improvements in Bottle-Blowing Machines, of which the following is a specification.

My invention relates to improvements in bottle blowing machines, and more particularly to improved mechanism for cutting off the molten glass as it is supplied to the molds.

A further object is to provide improvements of this kind in which the cutting operation is controlled by the downward pressure of the glass holding rod, so that by a single movement of the rod, the glass may be supplied to the mold and cut off.

20 This is a division of my application for patent filed April 3, 1912, and given Serial No. 688,213.

With these and other objects in view, the invention consists in certain novel features of construction and combinations and arrangements of parts as will be more fully hereinafter described and pointed out in the claims.

In the accompanying drawings: Figure 1 is a sectional plan view illustrating the location of my improved cutter in connection with my improved bottle blowing machine. Fig. 2 is a view in longitudinal section through the cutter, and Fig. 3 is a bottom sectional plan view on the line 3-3 of Fig. 2.

2 represents a supporting post around which a table 9 is mounted to turn and is given a step by step feed by means of suitable mechanism forming the subject matter of my pending applications, and hence need not be described here in detail, except to say that the molds 13 which are positioned radially on the table, are moved in turn to a position below my improved molten glass cutter which will now be described in detail.

The first operation is that of placing the molten glass in the mold, and this operation is performed by a workman who takes the glass from the molten mass in the ordinary way upon a rod, and this rod he holds above a ring 100 which extends through an opening 101 in a horizontal bar 102. This bar 102 is secured at one end to an upright post

103 and the latter at its lower end is fixed to a bracket 104 secured to base 1. On the lower face of bar 102, a sliding cutter 105 is mounted, and has a knife 106 at its free edge adapted to pass across the lower end of the collar 100, and into a grooved keeper 107. This movement of the cutter is caused by a lever 108 which is fulcrumed between its ends on a pin 109 in a bracket 110 depending from bar 102.

An arm 111 fixed to lever 108 is pivotally connected to the cutter 105. One end of lever 108 is forked and pivotally connected to a sleeve 112 adapted to slide on post 103. The sliding movement of this sleeve 112 is limited by collars 113 fixed to the post by set screws 114. The free end of lever 108 is connected to a plunger 115 which extends upwardly through a slot 116 in cutter 105, and through an opening 117 in the bar 102. A cross bar 118 is fixed to the upper end of plunger 115, and when this plunger is depressed by pressing the glass holding rod on the cross bar 118, the cutter will be operated to cut off the molten glass. In other words, the operator guides the glass through the ring 100, and when the proper amount is in the mold, he depresses plunger 115 with his rod, so that he cuts off just the amount of glass desired.

The cutter 105 is held in proper cutting position by means of a cross bar 119 through which bolts 120 project. These bolts extend through openings in bar 102, and have nuts 121 on their upper ends between which and the bar 102, coiled springs 122 are located and exert upward pressure on the cutter to hold it firmly against the under face of bar 102.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a supporting bar 105 having a glass guiding ring and an opening in rear of the ring, of a cutter mounted to slide against the lower face of said bar and

movable across said ring, said cutter having a longitudinal slot therein, a pivoted lever connected to said cutter, and a plunger passing through said opening in the bar and through the slot in the blade and connected to the lever, so that the depression of the plunger causes the pivoting of the lever and the sliding movement of the cutter, substantially as described.

35 2. The combination with a supporting bar having a glass guiding ring and an opening in rear of the ring, of a cutter mounted to slide against the lower face of said bar and movable across the ring, said cutter having 10 a longitudinal slot therein, a depending bracket on the bar, a lever fulcrumed between its ends on said bracket, an upwardly projecting arm on said lever connected to the cutter, a plunger passing through the 15 opening in the bar and the slot in the cutter, and connected to one end of said lever, and means at the other end of said lever limiting the pivotal movement thereof, substantially as described.

30 3. In combination with a glass guiding ring adapted to be supported above a mold ring in position to direct glass into the mold, a bar supporting said ring, a cutter mounted to slide below the bar, a plunger movable 20 by a rod holding the molten glass, a depend-

ing bracket on the bar, a lever fulcrumed on the bracket and to which said plunger is connected, and an arm on said lever connected to the cutter and adapted to move the cutter across the lower end of the ring when 35 said lever is actuated, substantially as described.

4. In combination with a molten glass cutter comprising a bar, a glass guiding ring in said bar, a knife mounted to slide 40 below the bar, a depending bracket on the bar, a lever fulcrumed on the bracket, an arm on said lever connected to the knife and adapted to move the knife across the lower end of the ring when said lever is moved, a 45 plunger connected to said lever and projecting through the bar and adapted to be depressed by a glass holding rod to move the lever, a post, a sliding sleeve on the post to which one end of said lever is pivotally 50 connected, and collars fixed to the post limiting the movement of the sleeve, substantially as described.

In testimony whereof I have signed my name to this specification in the presence of 55 two subscribing witnesses.

THOMAS C. DUFFIELD.
